UNITED STATES PATENT OFFICE

HERBERT G. SMITH, OF ROCHESTER, NEW YORK, AND THEODORE BURRICK, OF DETROIT,
MICHIGAN

FINGERPRINT APPARATUS

Application filed October 2, 1931. Serial No. 566,552.

This invention relates to apparatus for use in prisons, police departments, finger print bureaus and wherever it is desired to make finger prints for identification purposes.

5 One of the objects is to provide a device of this character which can be made either in portable or non-portable form and provide a simple and efficient means for making prints neatly, clearly, and quickly, thereby 10 effecting a considerable saving of time which can be devoted to classification and other incidental work.

Another object is to provide a compact structure containing at convenient points all 15 accessories necessary for the work.

A still further object is to enable the operator to readily and properly apply ink to stiff fingers, thereby covering a difficulty which has always confronted experts.

20 Another object is to provide efficient means for holding record cards while impressions are being made.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed may be made within the scope of what is claimed without departing from the spirit of the invention.

In the accompanying drawings the preferred forms of the invention have been 35 shown.

In said drawings:

Figure 1 is a plan view of a portable apparatus the cover being removed.

40 Figure 2 is a front elevation, the raised cover being broken away.

Figure 3 is a section on line 3-3, Figure 1, the cover being closed.

45 Figure 4 is a section on line 4-4, Figure 3.

Figure 5 is a horizontal section through one side portion taken on the line 5-5, Figure 3, the camera being shown in plan.

50 Figure 6 is a horizontal section taken on line 6-6, Figure 3, through the side portion

opposite to Figure 5, the camera being shown in plan.

Figure 7 is a front elevation of a modified form which is not portable.

Referring to the figures by characters of 55 reference, 1 designates a casing having a box-like lid 2 hinged thereto as at 3 and also provided with a front closure in the form of a hinged panel 4. Fasteners 5 on the lid and panel can be used for holding them closed. 60

A compartment 6 is provided in the back portion of the casing for holding desired accessories. For example a finger print camera 7 can be removably positioned therein. Other accessories can be secured in any manner desired within cover 2. As shown an 65 ink roller 8 can be held by a clip 9 and a rack 10 can be provided for holding film packs or plates, a magnifying glass, a sponge, brushes, etc. Under some conditions certain 70 of these supplies could be located in the box. This is a minor feature of the invention and a detailed description and illustration thereof is not deemed essential.

The printing apparatus per se includes a 75 housing 11 which is slidable into and out of casing 1 through the open front thereof. This housing can be provided with side cleats 12 slidable in guide grooves 13 provided therefor. The front 14 of the housing is closed except for an opening to receive a drawer 15 containing a spring 16 adapted to grip the back end of a pack of cards used for receiving prints. A raised portion 17 is located on the bottom of the drawer near 80 the front ends thereof for holding the front ends of the cards elevated where they can easily be engaged and lifted.

The back end of the housing 11 is closed as at 18 and an intermediate cross strip 19 is 85 located above the drawer. The top 20 of the housing is secured on the strip and on the front 14 and back 18. A compartment 21 can be formed between the back 18 and strip 19 and between top 20 and a supporting or bottom strip 22 located above the drawer. Openings 23 can be formed in the top 20 above this compartment to receive the lower 90 portions of bottles or other containers 24 holding ink, etc. If preferred, however, 100

these containers could be placed in other positions.

The top 20 of the housing 11 projects forwardly and forms a rounded gripping edge 25.

5 A strip 26 can be secured to the bottom of the projecting portion and constitutes a pull by means of which the entire housing 11 can be drawn from the casing 1 and placed on a table or the like for use.

10 Short longitudinal grooves 27 are formed in the inner faces of the sides of the housing 11 and receive and guide the ends of a slideable transverse bar 28. Rods 29 extend forwardly from this bar and are slideable in

15 the front 14. Their front ends are upturned and connected by a transversely bowed clamping strip 30 which is adapted to move toward and from the rounded front edge 25 of top 20 and to cooperate therewith to form 20 a clamp.

A transverse shaft 31 is journaled in the sides of housing 11 above drawer 15 and is provided at one end with a radial handle 32 projecting upwardly through a slot 33 in top 25

20. Spaced cranks 34 are provided in the shaft and each is connected by a pitman 35 to a lug 36 on bar 28. Springs 37 connect the bar 28 to strip 19 and serve to resist forward movement of the bar.

25 The parts are so located and proportioned that when handle 32 is pushed backwardly the cranks 34 will thrust through pitmen 35 against lugs 36 and bar 28 and cause the clamping strip 30 to move away from the front edge of top 20. At the same time the cranks will move slightly past a dead center with handle 32 bearing against one end of slot 33. Consequently the tensioned springs 37 will hold the parts in the positions to which

35 they have been moved. Thereafter, the handle 32 can be pushed forward slightly. This will be sufficient to move the cranks 34 downwardly past their dead centers and the springs will instantly snap the strip 30 to 40 clamping position.

Parallel guide rods 38 are supported above the side portions of top 20 and are connected thereto by end posts 39. A cover plate 40 extends over the curved front edge of top 20 and backwardly between the front portions of the rails where it has an inclined lip 41. The rails 38 are slideably engaged by the sides 42 of the ink block 43 which bears movably on the top 20. The sides are connected by 45 a bottom strip 44 the top of which is inclined downwardly and forwardly and carries a guide plate 45. This guide plate is also inclined and its back edge 46 is folded under so as to engage in the back of strip 44, as shown. The forward edge of the guide plate is adapted to enter between top 20 and lip 41 when the ink block is slid forwardly to the front limit of its movement.

50 The back portions of the sides 42 are connected by a cross strip 47 to the bottom of

which are secured the back ends of guide strips 48. These strips are inclined forwardly toward plate 45 and are adapted to overlie the side edges of a card (not shown) resting on the plate 45.

70 The top 49 of the ink block is secured on the sides 42 and strip 47 and is provided with a cover or platen 50 formed preferably of a smooth plate of glass. Guide cleats 51 are carried by the sides 42 beneath the front portion of top 50 and are slidably engaged by the ends of a cross bar 52 from the center of which depends a jaw 53.

75 A transverse shaft 54 is journaled in the sides 42 and has cranks 55 connected by pitmen 56 to lugs 57 on bar 52. The pitmen can be adjusted in length in any well known manner. Springs 58 connected to the pitmen serve to hold the cranks 55 either in lowered positions as shown in Figure 3 (at which time 80 jaw 53 is forced against top 20 or a card thereon), or in raised positions past their dead centers and against top 40. When they are in this latter position the bar 52 and jaw 53 are held elevated. The shaft can be actuated by 85 a handle 59 on one end thereof.

A clamping screw 60 is carried by one side of the ink block and is adapted to bind on one of the rails 38 to hold the block against movement.

90 In using this apparatus the housing 11 is slid out of casing 1 and placed on a table or the like although under some conditions it can be left in the open casing. A small quantity of ink is placed on the platen 50 and 100 then rolled so as to be spread in a thin film.

A card containing suitable spaces for receiving fingerprints is then removed from the drawer 15 and the ink block 43 is slid forwardly until stopped by the front posts 39. It is then secured by screw 60. Thereafter handle 32 is tripped forwardly to cause strip 30 to move away from the top 20. Handle 59 is swung upwardly and lifts jaw 53. The card is inserted between strip 30 and top 20 110

and also between plate 45 and jaw 53. After it has been flattened out and properly positioned the two handles are shifted to cause strip 30 and jaw 53 to snap into clamping positions. The fingers of the person to be 120

finger-printed are placed on the platen and then pressed on that portion of the card resting on the top 20. Strip 30 is then moved to releasing position, ink block 43 is unfastened and slid backwardly and the card will be drawn by jaw 53 back along top 20. This will bring another portion of the card onto the top 20. The strip 30 can then be released to clamp the strip, jaw 53 can be raised, and ink block 43 can be moved forwardly once more to slide plate 43 beneath the card and under lip 41. The jaw 53 is then released to clamp on the card and the operation already described can be repeated. After two or more reciprocations of the ink block and succes-

sive impressions on the card, said card will be fed rearwardly through the ink block and can then be removed and classified.

As has been stated, the device thus far described is of a portable nature. In large institutions the case 1 need not be used and the structure corresponding with housing 11 can be made larger for use on a desk or table. This larger size has been illustrated in Figure 7 and is of the same construction as that heretofore described with the exception of the location of the operating handles. As there is no outer casing the end of shaft 61, which corresponds with shaft 31, has a depending handle 62 at the side of the housing instead of the top thereof.

One of the advantages of the apparatus covered by this application is the ease with which stiff fingers can be printed. While one finger is being rolled on the inked platen the other fingers can be extended straight over bar 52 and beneath the top of the ink block. Thus a problem which has been difficult to overcome heretofore is met readily.

25. What is claimed is:

1. Fingerprint apparatus including a structure for supporting a card in position to receive prints, an ink block mounted for back and forth sliding movement thereon, and separately actuated clamping means for connecting the card to the ink block and to the supporting structure respectively.

2. Fingerprint apparatus including a structure for supporting a card in position to receive prints, an ink block mounted for back and forth sliding movement thereon, means carried by the ink block for clamping on the supporting card and moving it with the block, and means on the supporting structure for gripping the card to hold it against movement.

3. Fingerprint apparatus including a structure for supporting a card in position to receive prints, an ink block mounted for back and forth sliding movement thereon, a platen thereon, and a cross member slidably on the ink block and having a card gripping jaw, there being a finger receiving space between the platen and cross member.

50. 4. Fingerprint apparatus including a structure for supporting a card in position to receive prints, an ink block mounted for back and forth sliding movement thereon, a card gripping element carried by the ink block, yielding means for holding said element in either gripping or releasing position, and an operating device connected to said element.

55. 5. Fingerprint apparatus including a structure for supporting a card in position to receive prints, an ink block mounted for back and forth sliding movement thereon, a cross bar slidably connected to the ink block, a card gripping portion thereon, a shaft having a crank, a driving connection between the crank and the cross bar, said crank

being movable past a dead center in one direction to bring the gripping portion into card-gripping position and in the opposite direction to bring said portion to non-gripping position, means for shifting the shaft 70 to move the crank past its dead center, and yielding means for actuating the crank in either direction when moved past its dead center.

6. Fingerprint apparatus including a 75 structure for supporting a card in position to receive prints, an ink block mounted for back and forth sliding movement thereon, means carried by the ink block for gripping a card, and drawing it with said block when 80 moved along the supporting structure, a clamping strip cooperating with the supporting structure to grip a card, a shaft having a crank, a driving connection between the crank and strip, means for rotating the shaft 85 to move the crank in either direction past a dead center, and a spring for shifting the crank in either direction when moved past said dead center.

7. Fingerprint apparatus including a 90 structure for supporting a card in position to receive prints, an ink block mounted for back and forth sliding movement thereon, guide rails for the ink block, means on the block for engaging a rail to hold the block against 95 sliding movement, and separately actuated means on the block and structure respectively for gripping a card on the structure.

8. In a fingerprint apparatus a supporting structure, means at one end thereof for gripping a card resting on the structure, an ink block mounted for back and forth sliding movement on said structure, said block being open at the front and back for the reception and passage of the card, means in the block 100 for guiding the card, and means carried by the block for gripping the card and drawing it with the block when moved in one direction and while released by the first named gripping means.

9. In a fingerprint apparatus a card housing, a clamping strip shiftable relative to one end of the housing to receive and guide a card and to grip upon the card, yielding means for holding said strip in either guiding or in gripping position, an ink block 115 slidably on the housing, and means carried thereby for clamping on the card and for dragging the card over the housing when released from said gripping means.

10. The combination with a housing having separate card and ink-holding means, of an ink block slidable on the housing, card gripping means carried thereby for engaging a card and for drawing the card over the housing with the block, means on the housing for gripping the card, and separate means for actuating the respective card gripping means.

11. The combination with a casing, of a 130

housing slidable therein for supporting a card in position to receive fingerprints, an ink block mounted for back and forth sliding movement on the housing, and separately actuated card-gripping means carried by the housing and the ink block respectively.

In testimony that we claim the foregoing as our own, we have hereto affixed our signatures.

10
